UNITED STATES PATENT OFFICE.

WILLIAM HECKERT, OF FINDLAY, ASSIGNOR OF ONE-HALF TO BENJAMIN BUTTERWORTH, OF CINCINNATI, OHIO.

METHOD OF AND APPARATUS FOR HEATING HOT WATER AND STEAM.

SPECIFICATION forming part of Letters Patent No. 499,322, dated June 13, 1893.

Application filed February 1, 1893. Serial No. 460,527. (No model.)

To all whom it may concern:

Be it known that I, WILLIAM HECKERT, a citizen of the United States, residing at Findlay, in the county of Hancock and State of Ohio, have invented certain new and useful Improvements in Methods of and Apparatus for Heating Hot Water and Steam; and I do hereby declare the following to be a full, clear, and exact description of the invention, so such as will enable others skilled in the art to which it appertains to make and use the same.

The invention relates to steam boilers, and the objects are to provide an improved method of and apparatus for heating hot water and steam, whereby superior results are attained with but a small expenditure of fuel.

The invention consists essentially in an improved method of heating water or steam, which consists in applying the highest degree of heat resulting from the combustion of fuel to the hottest portion of the water or steam, so as to maintain the highest temperature at such point, and heating the remainder of the water within the boiler by causing the heated air and volatile products of combustion to issue from the combustion chamber at about said point of highest temperature and pass downwardly through an upwardly-moving current of water supply through successively

reduced temperatures to a point at which the minimum temperature is reached, and thence into the stack, whereby the heat discharged from the combustion chamber will be utilized in gradually increasing the temperature of the water in the direction in which the highest temperature is attained, while gradually reducing its own temperature in the opposite direction.

The invention consists further in an improved apparatus for carrying the aforesaid method into effect, and in certain features of construction and combinations of parts all as will be hereinafter described and particularly pointed out in the claims at the end of this description.

It has heretofore been the common practice to place the fire-box or combustion chamber under the boiler or as low as possible, so that the heat acts first upon the coldest stratum of water and the residue passes off at a point where the temperature in the boiler is high-

est, that is, the place where the steam is located, and at a higher temperature than that of the steam, thus leaving off its work at a point where it is most needed in order to intensify the heat of the steam and thus increase its pressure. As a result the greater portion of the heat, instead of being put to useful work, is wasted.

The primary object of my invention is to prevent this undue waste of heat and fuel, and to provide for its utilization to the fullest extent and also to better advantage than is possible in the use of boilers of ordinary construction.

One form of apparatus which may be employed in practicing the invention is illustrated in the accompanying drawings, which are to be taken as a part of this specification, and wherein—

Figure 1 represents a vertical longitudinal sectional elevation of the boiler or heater; and Fig. 2 a cross-section of the same; the section being taken on the line II—II of Fig. 1.

Similar letters of reference are used to denote similar parts of the apparatus.

A, denotes the fire-box or combustion chamber which may be surrounded by a water space a, a, and provided with a superimposed steam dome or chest B.

C, C, denote a series of pipes or flues for conducting the residue of heat and volatile products of combustion from the fire-box to the smoke stack or chimney D. These flues may consist of a continuous coil of pipe extending in a serpentine course from the inlet c, to the outlet c', thereof communicating with the stack, but I preferably use a series of pipe sections which may be connected at their ends by couplings C', uniting the outlet end of one section with the inlet end of the next succeeding section, and provided with a duct c², to establish communication between such ends. The pipes or flues C, C, are inclosed within larger pipes or flues E, E, the ends of which are connected by the couplings C', in the manner described with reference to the pipe sections C; the couplings being provided with ducts e, leading from the outlet of one pipe section to the inlet of the next succeeding section as shown. The heat flues are thus completely enveloped by the column

85
90
95
100

of liquid contained within the annular space surrounding the smaller flues, so that the heated column of air and products of combustion issuing from the discharge openings 5 in the combustion chamber and passing through said flues shall impart their heat to the column or columns of water surrounding said flues, and being thus gradually deprived of heat, in passing from a point at which the 10 water attains its highest temperature through successively reduced temperatures to a point of minimum temperature, pass into and out of the stack in a cold condition.

E' denotes the supply pipe communicating 15 with the lower pipe section E of the tubular boiler, and E², a valve for controlling the supply to said pipe.

F, F', denote a series of horizontal partitions or baffle-plates which extend alternately 20 from opposite ends of the boiler-inclosing casing and terminate a suitable distance from the end wall of the casing to provide an opening at such point for the passage of air, thus forming a zig-zag course for the introduction 25 of air to the combustion chamber.

G, denotes an opening or door for the admission of air to the air flues formed by the aforesaid partitions.

F², F² denote a series of vertically disposed 30 partitions separating the series of pipes E, E, and dividing the space within the boiler casing so as to form a corresponding series of flues or conduits for the air supply leading to the combustion chamber. The cold air enters the door G, and moving in the direction 35 of the arrows 1, Fig. 1, passes the horizontal partition or baffle plate F, above the lower flue at the open end f, of said plate, and then along the next tube and its partition F', past 40 the open end f', of said partition, and so on until it finally reaches the air space g, under the fire-box, communicating with the air space g', at the end of the fire-box, and enters the open end or ends of the air tube or tubes H, 45 H. The air tubes H, are provided with conical plugs or valves H', which are tapped through the side of the boiler casing and adapted to be screwed in or out for the purpose of regulating the supply of air to the 50 combustion chamber. Within the tubes H, H, may be fitted gas pipes h, h, which are provided with a series of gas jets or injectors h', for supplying gas to the combustion chamber. The plugs H' fit over the gas tubes h, 55 and may be adjusted along the same to vary the size of the opening for the admission of air as may be desired. It will thus be seen that the cold air entering at the door G, will absorb the heat radiated from the water tubes 60 E, E, between the successive horizontal partitions or baffle-plates and that at each upward step it reaches a higher temperature of radiated heat, coming finally to the highest temperature adjacent to the fire-box, which it 65 enters in a heated condition, thereby securing perfect combustion.

The boiler may be suitably incased in brick

work or provided with a covering of asbestos or other suitable material as shown, and if stationary, may be mounted on a suitable foundation of masonry, as illustrated in the drawings, but of course such parts of the apparatus form no part of my invention and the boiler is designed for general application, and may be either moving, as in the case of locomotives, or stationary, according to requirements.

From the foregoing description it will be seen that the entire heat resulting from the combustion of fuel in the combustion chamber is utilized to the best possible advantage. The fire-box being placed above the boiler and under the steam dome is in the hottest part of the water and gives off heat of the highest temperature at the point where it is most needed. From this point the residue of heat and volatile products of combustion pass downward through the heat flues and the current of water flowing upwardly in the annular space or spaces surrounding said flues, gradually imparting heat to the water and meeting colder water at each descending step. The cold water entering from below rises through the space or spaces between the smaller and larger flues and as it moves upward as shown by the arrows 2, comes in contact with a gradually rising temperature in the heat flues from which it gradually absorbs heat until it reaches the space surrounding the intensely hot fire-box. The inner column or columns of heated air are thus caused to move in an opposite direction to the movement of the column or columns of water, and by meeting colder water at each lower turn or step the volume of heated air is contracted and its specific gravity increased so as to bring about those conditions which permit the heat to pass from a higher to a lower temperature of water until all the heat is expended. On the other hand the water in receiving the heat from the heat flues is caused to expand and by a natural law rises in the tubes. The air being admitted at the base of the furnace and passing upward between the water pipes also absorbs any heat which may be radiated from said pipes and enters the fire-box in a heated condition, thereby securing perfect combustion and the development of the greatest possible heat from the fuel.

Another important advantage of this method of heating results from the fact that by locating the fire-box above the boiler the coldest water will be below, with a gradually decreasing temperature in the flues as the distance from the fire-box increases, so as to secure the conditions essential to the attainment of the best results and at the same time avoid the necessity for and disadvantages of a water circulation to protect the heat flues or pipes from burning.

In boilers of the usual construction, the fire being under the boiler, it is essential to secure a constant upward movement of the

heated water, which is replaced in turn by the return circulation, thereby preserving a nearly uniform temperature and protecting the highly heated parts of the heat flues or 5 pipes from burning, but at the expense of those conditions which are conducive to the best results. In my method, there being no circulation of the water either in a direct vertical line or open body, as in previous boiler 10 constructions, the temperature is not equalized, and I thereby secure the low temperature of water required to absorb heat from lower temperatures of the residue of heat or waste products of combustion passing through the 15 water-enveloped heat-flues, and thus produce independent currents of heat residue flowing down and water supply flowing up, thereby attaining the best results with but a small expenditure of fuel.

20 In some cases it may be found desirable to use only a single set of flues or pipes containing the water, and to cause the residue of heat and waste products of combustion to pass downwardly to the stack in a zig-zag 25 course between the baffle-plates or partitions and in contact with the outer sides of the water pipes, instead of permitting the air supply to pass upward along said zig-zag open space surrounding said pipes.

30 It will be understood of course that I do not desire to be limited in the application of my invention to any particular class or type of boilers or hot water or steam heating apparatuses, as the invention may be applied 35 in a number of ways without regard to any special form of apparatus for carrying the same into effect. And the same principles may be applied in hot air heaters, in which, however, but a single set of flues would be required; the inner tubes or flues being dispensed with. But this latter feature will 40 form the subject matter of an application filed concurrently herewith.

Having thus fully described my invention, 45 what I claim as new, and desire to secure by Letters Patent of the United States, is—

1. The method of heating hot water and steam, which consists in producing independent currents of heat residue flowing down 50 and through oppositely and upwardly moving enveloping currents of water supply; the ascending column of water being caused to flow in a direction opposite to the direction of motion of the heated currents only and 55 without circulation on the boiler so as to gradually raise the temperature of the water in the direction in which it is moving, and applying the heat of highest temperature in the combustion chamber to a highly heated 60 portion of water or steam at the head of the column, so as to maintain and intensify the heat at the latter point, substantially as described.

2. The method of heating hot water and 65 steam and maintaining the steam at a high pressure, which consists in applying the heat from the fire-box at its highest temperature

to the hottest portion of a heated column of water or steam, and heating the column of water from such point of high temperature to 70 a point of lower temperature by passing the residue of heat and products of combustion through the major part of the liquid column in a direction opposite to the direction in which the water is moving, and in a zig-zag 75 course downwardly from the fire-box to the base of a stack or outlet flue for the heat, and simultaneously supplying heated air to the fire-box by admitting air at the base of the boiler and conducting the same upwardly in 80 a zig-zag course in contact with the hot boiler pipes from a point of lower temperature to the point at which the fire-box is located, whereby the residue of heat from the fire-box is gradually expended in raising the temperature 85 of the water and air in the direction of the highest temperature attained while moving in an opposite direction to the direction of motion of the air and water, substantially as described.

3. The method of heating water and steam and supplying air to support combustion, which consists in passing the contents of a combustion chamber downwardly through an ascending enveloping column of water and 90 effecting an upward current of air from the base of the liquid column in contact with the hot boiler pipes leading to a water space or jacket surrounding the fire-box, substantially as described.

4. In combination with the tubular boiler, the fire-box placed at the top thereof and provided with a water space surrounding the same and with a superimposed steam dome, the stack, and the heat flues extending downwardly through the boiler tubes from the fire-box to the base of the stack, substantially as described.

5. A hot water and steam heating apparatus comprising the tubular boiler, the fire-box 110 mounted thereon and provided with a surrounding water space and superimposed steam dome, the stack, and the heat flues connecting said fire-box with the base of the stack through the boiler tubes, substantially as described.

6. A hot water and steam heating apparatus comprising a series of boiler pipes extending in a zig-zag course upwardly from a supply pipe to a fire-box placed at the top of the 115 boiler, said fire-box being provided with a water space surrounding the same and communicating with the upper tubular section of the boiler, and the heat flues extending through said boiler pipes from the fire-box to 120 the base of a stack or exit flue at the bottom of the boiler, substantially as described.

7. A hot water and steam heating apparatus comprising the tubular boiler having the fire-box mounted thereon and provided with a 130 surrounding water space and superimposed steam dome; said boiler consisting essentially of a series of water pipes extending downwardly in a zig-zag course from said water

space to the inlet to the boiler, a stack, and a corresponding series of heat flues inclosed in said water pipes and connecting the fire-box with the base of the stack, substantially as described.

8. The tubular boiler having the fire-box placed at the top thereof and consisting of a series of pipe sections extending in a zig-zag course from a supply pipe to a water space 10 surrounding the fire-box and a corresponding series of heat flues passing through said pipe sections downwardly from said fire-box to the exit end thereof, in combination with the baffle-plates and air inlet providing a serpentine 15 conduit for supplying heated air to the fire-box by contact of the air with the hot water pipes of the boiler, substantially as described.
9. The combination of the boiler tubes having the fire-box placed at the top thereof and 20 provided with a surrounding water space and a superimposed steam dome, together with heat flues inclosed in said tubes, and the vertical and horizontal partitions or baffle-plates inclosing the boiler tubes so as to form a zig-zag conduit for supplying heated air to the 25 fire-box, substantially as described.

10. In combination with the boiler tubes and heat flues inclosed therein, the fire-box

mounted at the top of the boiler, the air supply conduits leading from the bottom of the 30 boiler in contact with the boiler tubes to an air space adjacent to said fire-box, the air pipes communicating with said air space, and the adjustable conical valves for controlling the admission of air, substantially as de- 35 scribed.

11. In combination with the boiler tubes and heat flues inclosed therein, the fire-box mounted at the top of the boiler, the air supply conduits leading from the bottom of the 40 boiler in contact with the boiler tubes to an air space adjacent to said fire-box, the air pipes communicating with said air space, and the adjustable conical valves for controlling the admission of air, together with the gas 45 pipes extending through said air pipes and provided with a series of gas jets for directing commingled air and gas into the combustion chamber, substantially as described.

In testimony whereof I affix my signature in 50 presence of two witnesses.

WILLIAM HECKERT.
